LIGHTING FIXTURE

Richard Orth, Philadelphia, Pa., assignor to Gill
Glass & Fixture Company, Philadelphia, Pa., a
corporation of Delaware

Application May 1, 1941, Serial No. 391,297

2 Claims. (Cl. 240—78)

The present invention relates to lighting fixtures.

The present invention contemplates fluorescent lighting fixtures of the type usually suspended below the ceiling and adapted for both direct and indirect lighting.

According to the present invention the body of the fluorescent lighting fixture which supports the lamp sockets and lamps is provided with end plates considerably wider than the spacing of the lamps and extending below the lamps. These end plates are employed to support side panels to be made of glass or other light diffusing material, and these panels are preferably mounted so that they can be moved from an upper position where they hide or screen the lamps to a lower position where the lamps are accessible for replacement.

The present invention also contemplates lighting fixtures of the type above referred to wherein the space below and between the lower edges of the side panels is occupied by a plurality of light transmitting and diffusing rods or tubes.

The accompanying drawing shows, for purposes of illustrating the present invention, an embodiment in which the invention may take form, it being understood that the drawing is illustrative of the invention rather than limiting the same.

In the drawing:

Figure 1 is a perspective view of a lighting fixture;

Figure 2 is a transverse sectional view through the fixture;

Figure 3 is a fragmentary longitudinal section taken on the line 3—3 of Figure 2; and

Figure 4 is a view similar to Figure 2 showing a modified form of construction.

Where the fixture is intended to be mounted below the ceiling it is supported from a canopy such as indicated at 10. The fixture body includes a horizontal trough shaped sheet metal member 11 which supports downwardly and outwardly extending lamp sockets 12. This trough-like member is provided with a cover indicated at 13 and is stiffened at the ends by cross straps 14. It also has intermediate stiffening cross straps not shown.

End plates 15, 15 are secured to the cross straps 14 by screws indicated at 16, 16 and by screws 17 passing through the body 11 and into lugs 18 integral with the end plates. It will be noted from the drawing that the end plates 15, 15 extend laterally beyond the lamps 19 carried in the sockets 12 and below these lamps.

Sheet metal plates 20, 20 of L-shaped cross

section are pivotally secured to the lower part of the end plates 15 by screws indicated at 21. The plates 20 have arcuate slots 22. Bolts 23 having thumb nuts, such as indicated, are secured to the end plates and pass through the slots 22. The plates 20, 20 may be secured in the upper position, as shown in the front of Figure 1, and the left of Figure 2, or may be lowered to the position shown at the right of Figure 2 and at the rear of Figure 1. The plates 20, 20 support diffusing panels 24 usually made of glass and decorated or rendered light diffusing in any convenient manner. They are held in place by clips bent over as indicated at 25.

The lower central part of the plates 15 are provided with narrow inwardly extending flanges 26 employed for supporting a plurality of longitudinally extending glass tubes or rods 27. These rods close off the gap between the side panels, allow the downward transmission of light and sufficiently break up the downwardly transmitted light to conceal the interior of the fixture. They also provide a desirable decorative feature of the fixture.

In the modification shown in Figure 4 the end plate 30 is similar to the end plate 15 but is carried down nearer to a point directly under the center of the fixture. The side panels 31, 31 are pivoted, as indicated at 32, 32, and may be swung up and down in the same way as above described. Instead of closing off the gap between the side panels with the glass rods or tubes the construction of Figure 4 contemplates the use of a metal piece 33 which may be supported in any convenient manner between the two end plates.

Where the fixture is intended for mounting close to the ceiling it will be mounted with the cover plate 13 adjacent the ceiling line.

Fixtures made as above described present a pleasing appearance whether lighted or unlighted and the lamps and interior of the fixture will be screened against observation. The panels 24 will act as reflectors to increase the indirect lighting component depending upon the reflection factor of the panels. They may be readily lowered for lamp renewal and for cleaning.

It is apparent that, within the scope of the invention, modifications and different arrangements may be made other than is herein disclosed, and the present disclosure is illustrative merely, the invention comprehending all variations thereof.

What is claimed is:

1. In a fluorescent lighting fixture adapted for overhead mounting, a long, narrow horizontal

body, end plates fixedly secured to the ends of the body and extending laterally at each side of the body and below the body, pairs of fluorescent lamp sockets fixedly supported adjacent the end plates for carrying fluorescent lamps outside the body and inside the edges of the end plates, fluorescent lamps in the sockets, movable plates pivotally secured to the end plates below the body and swingable about horizontal axes, light diffusing panels extending between and carried by the movable plates, the panels being close to the lamps and extending up outside the lamps when

in the upper position to provide lateral screens for the lamps and being swingable downwardly to space them from the lamps to facilitate cleaning and permit lamp removal, and means to hold the movable plates in either extreme position.

2. A fixture such as claimed in claim 1, wherein the movable plates are generally triangular shaped pieces of sheet metal and have inwardly extending flanges against which the diffusing panels are secured.

RICHARD ORTH.
